UNITED STATES PATENT OFFICE

2,391,303

PROJECTILE

Patrick Hamilton Field, Washington, D. C., assignor, by direct and mesne assignments, of one per cent to Stanley F. Clark, West New Brighton, N. Y., and ninety-nine per cent to Margaret Kinsler Liebert, Washington, D. C.

Application October 22, 1941, Serial No. 416,116

1 Claim. (Cl. 102—56)

This invention relates to projectiles, and has for the primary object the provision of an explosive projectile of the 50 caliber size, presenting great destructive power from the comparatively small amount of explosive contained therein, especially adapting its use to automatic guns on the 50 caliber craft, and is extremely convenient to handle with safety, further adapting itself to the use as above specified.

Another object of this invention is the provision of a safe firing means for the explosive within the projectile which will only operate on impact of the projectile with a target, bringing about explosion of the projectile during actual contact with the target so that damage thereto will be sufficient to substantially destroy the target, consequently adapting itself admirably for the destruction of armament which is of a self-sealing character commonly employed in the manufacture of fuel tanks, cars and other equipment of war airplanes and other war mechanized devices.

With these and other objects in view, as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a side elevation illustrating a projectile constructed in accordance with my invention;

Figure 2 is a sectional view taken on the line 2—2 of Figure 1;

Figure 3 is a transverse sectional view taken on the line 3—3 of Figure 1;

Figure 4 is an end elevation illustrating a detonator carrying plug;

Figure 5 is a side elevation illustrating a closure plug forming the butt end of the projectile;

Figure 6 is a fragmentary vertical sectional view showing a portion of a hammer supporting sleeve with the hammer disclosed in dotted line;

Figure 7 is a side elevation illustrating a modified form of my invention;

Figure 8 is a sectional view taken on the line 8—8 of Figure 7;

Figure 9 is an end elevation showing the front or nose end of the projectile;

Figure 10 is a transverse sectional view taken on the line 10—10 of Figure 8;

Figure 11 is a perspective view illustrating a firing pin.

Referring in detail to the drawings, the numeral 5 indicates the body of the projectile provided with the usual pointed front or forward end A and the butt or rear end B. The butt or rear end is in the form of a flanged closure plug 6 employed for closing a bore arranged longitudinally of the body. The plug 6 threads into the body. A slight taper or reduction in the diameter of the body is provided at the butt end to facilitate the application of a shell to the projectile body.

The bore extends into the forward end portion of the body and is reduced in diameter to form an explosive chamber 7. "Tenthrite" explosive is arranged in the chamber 7 and held therein by a packing disc 8 afforded or provided with an opening 9. The major portion of the bore of the body 5 is screw threaded and a detonator carrying plug 10 is threaded in the bore against the packing. The plug 10 is provided with a bore 11 extending axially thereof in which is mounted a detonator 12.

A hammer carrying sleeve 13 is threaded in the bore against the plug 10 and is abutted by the closure plug 6. The plug 10 and sleeve 13 are provided with wrench sockets 14 adapted for the reception of a spanner type wrench.

The sleeve 13 in its end which abuts the plug 6 is provided with notches 15 to receive pins 16 of a hammer 17 slidable in the sleeve 13. The pins 16 are fragile and normally sustain the hammer against sliding movement in the sleeve in the direction of the detonator. However, when the projectile strikes a target the impact shears the pins 16 so that the hammer may slide and strike the detonator with considerable force bringing about ignition of the explosive, the explosion of which shatters the body 5 so as to bring about substantially complete destruction of the target. The target thus destroyed if of the self-sealing armor type will be rendered incapable of its self-sealing action thereby admirably adapting the projectile for the destruction of important units of military mechanized devices which are frequently constructed of armament if only punctured will become self-sealed. Therefore, it will be seen that this projectile will be especially useful in defense against airplanes, tanks and other military mechanized devices.

Referring to my modified form of the invention, the body of the projectile is indicated by the character 5' and its shape is in accordance with the shape of the body 5, and also includes the butt closure plug 17 for sealing the open end of the bore of the body. The bore of the body has

portions thereof screw threaded and one portion unthreaded for the reception of the explosive 18. Packing discs 19 are arranged at each end of the explosive within the bore. A detonator carrying plug 20 is first threaded into the bore before placing the explosive in the space of the bore provided therefor. The plug 20 carries the detonator 21 operated by a firing pin 22 projecting a limited distance beyond the nose or front end of the body 16. The firing pin 22 is frictionally engaged with the wall of a complementary axial opening which latter extends from the pointed end of the projectile body to the bore of the plug 20. The other screw threaded portion of the bore is closed by an elongated externally screw threaded plug 23 arranged in abutting engagement with the closure plug 17. The plug 23 is provided with wrench engaging sockets 24.

On contact of the projectile with a target the firing pin 22 is driven against the detonator which in turn sets off the explosive 18 shattering the body 16 at the target bringing about substantial destruction of the target.

"Tenthrite" explosive is preferably used because it creates an intense heat and flames which

would ignite gaseous fuel so that if the projectile strikes a fuel tank it will be set on fire burning up any parts of the target which should not be destroyed by the explosion.

While I have shown and described a preferred embodiment of my invention, it will be understood that minor changes in construction, combination and arrangement of parts may be made without departing from the spirit and scope of the invention as claimed.

What is claimed is:

In a projectile, a metallic body having a bore a portion of which provides an explosive chamber, an explosive in said chamber, a plug threaded in the bore and carrying a detonator located adjacent the explosive, a sleeve threaded in the bore against the plug, a hammer slidable in the sleeve for actuating the detonator by impact of the body against a target, fragile means normally sustaining the hammer against movement in the sleeve and shearable by said impact, and a closure plug threaded in the bore against the sleeve and providing a butt end to said body.

PATRICK HAMILTON FIELD.
